NORMAN H. NYE, OF CUYAHOGA FALLS, OHIO, ASSIGNOR TO THE VAUGHN MACHINERY COMPANY, OF CUYAHOGA FALLS, OHIO, A CORPORATION OF OHIO

DISTRIBUTING APPARATUS FOR SPOOLERS ON WIRE DRAWING MACHINES

Application filed July 9, 1929. Serial No. 376,968.

The present invention relates to the spooling, and while it is particularly adapted and intended for use as an attachment for wire drawing machines, the invention may be extended to other fields.

The object of the invention is to design a form of distributing apparatus which is adaptable for use with wire drawing machines which will smoothly and evenly lay the wire on the spool and is capable of being easily adjusted to suit varying lengths of spools. The machine described and illustrated herein is highly efficient for the purposes described and is particularly adapted for use in connection with high speed wire drawing machines. The invention comprises a self-contained unitary distributing apparatus which is adapted for use with a separate motor which is unconnected with the remainder of the machine. While the invention is set forth in detail, it will be understood that exact conformity therewith is not essential to the successful practicing of the invention and changes and modifications may be made therein within the scope of the invention and the claims.

In the drawings in which the preferred form of the invention is shown,

Figure 1 is an end view of the distributing attachment for a wire drawing machine showing its relation to the spool;

Figure 2 is a vertical section on the line 2—2 of Figure 1;

Figure 3 is a horizontal section through the switch box, taken on the line 3—3 of Figure 2;

Figure 4 is a vertical section on the line 4—4 of Figure 3; and

Figure 5 is a transverse section through the feeding mechanism.

In the drawings, the wire drawing machine is not shown, as the invention is adaptable for any well known or standard form of machine. The spool is indicated at 10, being mounted at the delivery end of the machine and rotated by any suitable mechanism, the wire being indicated at 11. On its passage to the spool, the wire is guided by fingers 14 which are mounted on a projection from a reciprocable carriage 15,

the guide extending through a slot 16 in the carriage housing 17.

The carriage 15 is movable to and from over guide shafts 20 which are mounted in the housing on opposite sides of a screw 55 threaded shaft 21, which is driven in opposite directions by a reversing motor.

The shaft is in screw threaded engagement with a sleeve 22 located within the housing and held in position by ball bearings 23. A shoe 24 mounted in the housing bears against the outer surface of the sleeve, being forced into frictional engagement therewith by means of the coil spring 25, the force of which is adjusted by means of the screw threaded cap 26. The spring is adjusted so that during the normal operation of the distributor, the carriage is fed back and forth along the spool axis, depending upon the direction of rotation of the shaft, but should an obstruction be encountered, or the current be shut off from the motor for any reason, whereby the parts may continue to rotate without reversal at the proper time, the frictional engagement of the shoe 70 will permit the sleeve to rotate within the housing and thereby prevent breakage of the device.

At one side of the path of travel of the carriage is located the shiftable, non-rotatable rod 28, the ends of which are carried in sleeves 30, movable axially in bearings in the carriage housing. Projecting from the carriage is a fork 32 which surrounds the lower half of the rod. At its ends the rod is provided with the two screw-threaded portions 33, on which are mounted elongated nuts 34 having gear teeth cut in their outer surfaces, these nuts being located in the path of the fork 32, at either end of travel 80 of the carriage.

The position of the nuts 34 is adjusted along the screw threaded portions, so as to adapt the machine for varying widths of spools, the machine being thereby adjustable for laying the wire against the spool flanges within variations usually found in spools. Each nut is provided with gear teeth on its outer surface which extend the entire length of the nut, and these teeth are 100

- engaged by idler gears 35 which are rotated through pinions 36 mounted on shafts 37 having hand wheels 38 thereon. The face of the hand wheels are toothed or knurled, being engaged by spring detents 39. By rotation of the hand wheels, the nuts are moved to the desired position along the rod. At a midway point on the rod 28 is located a pin 40, which is received between the two spaced forks 42 formed on an arm 44 which is keyed to a vertical shaft 45, the latter being mounted in a bearing on the lower side of a switch box 46 received over an opening in the housing. The shaft 45 at its upper end is keyed to an angular lever 48, one arm of which is formed with a V-shaped tail piece 50 in contact with the conical end of a sliding pin 52 mounted in a bearing 54 in the side of the switch box. This pin is forced outwardly by a coil spring 55. As the lever 48 is rocked about its center, the pin 52 will be depressed until its point passes the vertex of the tail piece or cam, whereupon the lever is snapped over to its other position. This device not only assures a quick movement of the lever, but also moves and maintains the lever in its proper position at either end of its movement. It will be seen that the shaft 45 with the two levers attached thereto operates as a double lever.
- The other arm 58 of the lever is provided with a pin 60 which projects upwardly therefrom and into a slot 62 on a pivoted switch arm 63 of insulating material. The arm has a bushing 65 and is rotatable upon a shaft 64 projecting downwardly from the top of the switch box. The switch arm carries opposite spring contact arms 68 which move over and make electrical contact with the contact buttons 70 on the under side of the cover of the switch box. These contact buttons are electrically connected to the motor, so that the motor is reversed when the switch is thrown from one side to the other.
- The operation of the apparatus will be briefly described. As the spool is rotated to wrap the wire therearound, the carriage is moved to and fro between the limits of the spool flanges, laying the wire evenly over the whole extent of the spool. The carriage is moved by the rotation of the shaft 21 in opposite directions according to the direction of rotation of the motor. At each end of carriage travel, the fork 32 strikes one of the nuts 34, shifting the rod 28 and rocking the lever 48 past the pin 52. As the lever moves to the position where it is snapped over, the pin 60 moves freely in the slot so that no motion is transmitted to the switch arm until the lever is ready to snap over, and owing to the lost motion thus obtained, the switch is moved with a snap and arcing is avoided, the gap in the fork 42 permitting this movement. As the switch lever moves from one position to the other, the direction of rotation of the motor and the feed screw is reversed.
- What is claimed is:
1. In an apparatus of the character described, a spool and a distributor including a guide movable to and fro parallel to the spool axis, a screw shaft to move the guide, a reversible motor connected to the shaft, a reversing switch, and means operable by the guide at the limit of its movement to snap the switch and thereby reverse the direction of the motor. 70
  2. A spool, a guiding means movable to and fro parallel to the spool axis, a screw shaft to move the guiding means, a reversible motor connected to the shaft, a shiftable rod parallel to the screw shaft, means connected to the carriage and movable along the rod, stops on the rod, and a motor switch movable by the shifting of the rod. 80
  3. A spool, a guiding means movable to and fro parallel to the spool axis, a screw shaft to move the guiding means, a reversible motor connected to the shaft, a shiftable rod parallel to the screw shaft, a portion of the carriage being movable along the rod, stops on the rod, means for adjusting the position of the stops, and a motor switch movable by the shifting of the rod. 90
  4. In a spooling apparatus, a spool, a carriage movable to and fro parallel to the spool axis, a screw shaft, a sleeve in the carriage threaded on the shaft, and a frictional element bearing against the sleeve and normally preventing its rotation thereon. 100
  5. In a distributing apparatus, a rotatable spool, a guiding means movable to and fro parallel to the spool axis, a screw shaft to move the guiding means, means for rotating the shaft in opposite directions, a switch to control the direction of rotation of the shaft, a shiftable rod parallel to the screw shaft, adjustable stops on the rod, connections from the rod to the switch, and means to shift the rod at the limits of movement of the guiding means. 105
  6. In a distributing apparatus, a rotatable spool, a guiding carriage movable to and fro parallel to the spool axis, a feed screw for moving the carriage, a reversible motor connected to the feed screw, a switch to control the direction of the motor, a shiftable rod parallel to the screw shaft, a portion of the carriage being movable along the rod, a rotatable lever operable by the rod, a spring adapted to move the lever after a limited movement of the lever by the rod, and a connection between the lever and the switch 120 permitting relative movement of the lever and the switch. 115
  7. In a distributing apparatus, a rotatable spool, a guiding carriage movable to and fro parallel to the spool axis, a feed screw. 130

for the carriage, a reversible motor connected to the feed screw, a switch to control the direction of the motor, a shiftable rod parallel to the screw shaft, a portion of the carriage being movable along the rod, a lever operated by the rod and having provision for relative movement with respect to the rod, a switch and connections permitting relative movement between the switch and the lever, and a spring acting upon the lever to cause a quick movement of the lever and switch after a limited movement of the lever by the rod.

8. In a distributing apparatus, a rotatable 15 spool, a guide movable to and fro parallel to the spool axis, a feed screw for the guide, a reversible motor connected to the feed screw, a switch to control the direction of the motor, a shiftable rod parallel to the screw shaft, means connected to the guide and movable along the rod, a lever operated by the rod and having provision for relative movement with respect to the rod, a switch and connections permitting relative movement 25 between the switch and the lever, a cam surface on the lever, and a spring actuated pin bearing against the cam surface.

9. In a distributing apparatus, a rotatable spool, a guide movable to and fro along the 30 axis of the spool, a feed screw for the guide, a reversible motor for the feed screw, a switch for controlling the motor, a lever for the switch, a shiftable rod parallel to the feed screw, and movable by the guide, a 35 double lever having a fork, a pin on the rod and located in the fork but movable therein, a pin on the lever and a slot in the switch in which the pin is movable, and a spring device to cause movement of the lever and 40 switch independently of the movement of the rod.

10. In a distributing apparatus, a rotatable spool, a guide movable to and fro along the axis of the spool, a feed screw for the 45 guide, a reversible motor for the feed screw, a switch for controlling the motor, a lever for the switch, a shiftable rod parallel to the feed screw, and movable by the guide, a double lever having a fork, a pin on the rod 50 and located in the fork but movable therein, a pin on the lever and a slot in the switch in which the pin is movable, and a spring device to cause movement of the lever and switch independently of the movement of the 55 rod after a limited movement of the lever by the rod.

11. In a distributing apparatus, a rotatable spool, a guide movable to and fro along the axis of the spool, a feed screw for the 60 guide, a reversible motor for the feed screw, a switch for controlling the motor, a lever for the switch, a shiftable rod parallel to the feed screw, and movable by the guide, a double lever having a fork, a pin on the rod and located in the fork but movable

therein, a pin on the lever and a slot in the switch in which the pin is movable, a cam surface on the lever, a spring actuated pin bearing against the said surface and operating to move the lever after a limited movement thereof by the rod. 70

12. In a distributing apparatus, a rotatable spool, a guide movable to and fro along the axis of the spool, a feed screw for the guide, 75 a reversible motor for the feed screw, a switch for controlling the motor, a lever for the switch, a shiftable rod parallel to the feed screw, adjustable stops on the rod engageable by the guide at the limits of its movement, a double lever having a fork, a pin on the rod and located in the fork but movable therein, a pin on the lever and a slot in the switch in which the pin is movable, and a spring device to cause movement 80 of the lever and switch independently of the movement of the rod. 85

13. In a distributing apparatus, a rotatable spool, a guide movable to and fro along the axis of the spool, a feed screw for the guide, a reversible motor for the feed screw, 90 a switch for controlling the motor, a lever for the switch, a shiftable rod parallel to the feed screw, adjustable stops on the rod engageable by the guide at the limits of its movement, a double lever having a fork, a pin on the rod and located in the fork but movable therein, a pin on the lever and a slot in the switch in which the pin is movable, a cam surface on the lever, a spring actuated pin bearing against the said 95 surface and operating to move the lever after a limited movement thereof by the rod. 100
